UNITED STATES PATENT OFFICE

REUBEN ECKSTEIN, OF NEW YORK, N. Y.

ELECTRIC LAMP SOCKET

Application filed April 16, 1927. Serial No. 184,279.

This invention relates to electric lamp sockets for Christmas tree lighting outfits and the like purposes and a method of making same.

It is the object of this invention to generally simplify the construction and method of manufacture of lamp sockets of the character described. More particularly, the invention contemplates the provision of a lamp socket of such character in which the parts are assembled in a simple and quick manner to form a rugged, practical structure and yet permit of ready disassembly thereof if on testing the assembled socket, defects appear.

This reduces to a minimum the usual manufacturing losses due to defective assembly.

A further object of the invention is to provide a lamp socket of the character described, comprising few and simple parts, which shall be comparatively cheap to manufacture, and practical and efficient to a high degree in use; and further to provide a process for the making of such device which may be simple, cheap and economical to carry out.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a cross-sectional view of an electric lamp socket embodying the invention showing the interior construction;

Fig. 2 is a cross-sectional view of the body of the improved electric lamp socket showing the shell contact moulded therein;

Fig. 3 is a front elevational view showing the lamp socket in the course of assembly;

Fig. 4 is a cross-sectional view taken on line 4—4 in Fig. 1; and

Fig. 5 is an enlarged detail view of the removable plate terminal.

Referring in detail to the drawings, 10 denotes an electric lamp socket embodying

the invention. Said socket comprises a body 11 made of insulating material, such as "Bakelite", suitably shaped and molded. Said body 11 includes a cylindrical side wall 12 and an end wall 13 forming a housing for the current carrying parts of the socket.

Moulded in the socket body interiorly of said walls is the current carrying screw contact shell 14 adapted to receive the base 26 of a bulb B in the well understood manner, said shell being provided with an inwardly turned rim portion 15 at the wall 13 of the socket to form a seat for other current carrying parts in the manner hereinafter to appear.

A lead 16 extends through a passage 17 in the wall 13, and has its end soldered or otherwise secured in an opening 18 of a terminal plate 19. The latter has a segmental flange 20 bearing on the rim portion 15 which provides a substantial contact therewith for connecting the shell 14 to one side of the electrical supply through said lead 16. The portion of said plate 19 forming the rim of the opening 18 may be extended downwardly into the passage 17 so as to be engaged therein for retaining the terminal plate 19 against lateral shifting thus providing reliable contact with the shell rim portion 15.

A center contact 21 is provided in the socket 10 which is seen to comprise an eyelet 22 connected to the other lead 23 from the power supply, said eyelet being mounted centrally to extend through an insulating disc 25 fitted into the contact shell. The lead 23 extends through a passage 24 in the socket wall 13 parallelly spaced from the passage 17 and is soldered or otherwise suitably connected to the eyelet. A second insulating disc 26 perforated centrally to receive the lead 23 is disposed beneath the disc 25 to effectively insulate terminal plate 19 from the center contact 21 or any exposed portion of the lead 23. The insulating discs closely overlie the terminal plate 19 and are snugly fitted in the contact shell for retaining the socket parts in assembly.

The novel method of manufacturing the improved electric lamp socket 10 will now be described. The contact shell 14 is moulded

directly into the body 12 of the socket, thus forming a unitary structure therewith. The leads 16 and 23 are then inserted through the passages 17 and 24, respectively. The terminal plate 19 and the center contact 21 are then soldered to their respective leads 16 and 23, respectively, the lead 23 being first threaded through the insulating disc 26. The leads 16 and 23 are next pulled down to seat the terminal plate 19 on the shell rim 15 and to fit the center contact into the socket with the insulating disc 26 interposed between the terminal plate and the center contact, as is clearly shown in Fig. 1. The current carrying parts of the lamp socket are then compactly fitted in position in the shell and said socket is ready to receive the base 27 of a bulb B, said parts being tightly clamped together on screwing the lamp base into the shell 14.

The improved method of construction described above permits the disassembly of the current carrying parts in case the lamp socket when tested proves defective. This is a valuable improvement in the manufacture of relatively inexpensive class of lamp sockets whereof the current carrying parts are generally secured permanently together in the assembling thereof and consequent defective lamp sockets are rejected and scrapped since it does not pay to disassemble, locate and replace the defective parts. This loss is entirely eliminated in the improved construction above described since the parts may be readily dismounted, inspected and any defective part replaced.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. An electric lamp socket comprising a body of insulating material having an end wall, a contact shell in said body extending down to said end wall adapted to receive the base of a bulb, said shell having an inwardly turned rim portion at said end wall, a terminal plate having a flange seated on said rim portion for connecting the shell to one side of the electrical supply, a center contact for the socket, and an insulating disc detachably fitted in the shell and demountably supporting said center contact, said insulating disc bearing against the terminal plate to retain the flange thereof in contact with the rim portion of the shell.

2. An electric lamp socket comprising a body of insulating material having an end wall, a contact shell embedded in said body and against said wall adapted to receive the base of a bulb, said shell having an inwardly turned rim portion at said wall, said wall having passages adapted to receive leads for connecting the socket to a source of electrical supply, a terminal plate having an extension flange seated on said rim portion connecting the shell to one of the leads, said terminal plate having a projecting portion extending into one of said passages to retain said plate against displacement.

3. In an electric lamp socket, the combination of a contact shell having an inwardly extending basal rim portion and a terminal plate for connecting said shell to one side of the electrical supply, said plate having a rim portion seated on said shell rim.

4. In an electric lamp socket, in combination with an insulating body and a contact shell imbedded in said body, said shell having an inwardly turned basal rim portion, of a terminal plate seated on said rim portion and connected to a lead wire extending thru said body, an insulating disc having an opening therein seated on said terminal plate, and a central contact member seated on said insulating disc, said central contact member being secured to a lead wire extending thru said opening and said body.

In testimony whereof I affix my signature.

REUBEN ECKSTEIN.
